DESIGN FOR A COMBINED DISPLAY AND STORAGE CABINET FOR KNITTING PINS OR THE LIKE

Edward D. Davis, Chicago, Ill., assignor to The
Boye Needle Company, Chicago, Ill., a corpora-
tion of Illinois

Application March 17, 1941, Serial No. 99,647

Term of patent 14 years

To all whom it may concern:

Be it known that I, Edward D. Davis, a citizen of the United States, residing at Chicago, county of Cook and State of Illinois, have invented a new, original, and ornamental Design for a Combined Display and Storage Cabinet, for Knitting Pins or the like, of which the following is a specification, reference being had to the accompanying drawing, forming a part thereof, in which:

Figure 1 is a front elevational view of a com-

bined display and storage cabinet, for knitting pins or the like, showing my new design; Figure 2 is a top perspective view; and Figure 3 a side elevational view of the same.

I claim:

The ornamental design for a combined display and storage cabinet for knitting pins or the like, as shown.

EDWARD D. DAVIS.
